UNITED STATES PATENT OFFICE.

VICTOR V. PESSEMIER, OF TACOMA, WASHINGTON.

SHOE LAST.

Application filed August 24, 1926. Serial No. 131,238.

This invention relates to a shoe last, designed primarily for use in connection with the well known type of McKay shoe stitching machines, but it is to be understood that 5 a shoe last, in accordance with this invention, can be employed in connection with any form of shoe stitching machine for which it is found applicable, and the invention has for its object to provide, a shoe last 10 in a manner hereinafter set forth whereby the sole of a shoe, pump or oxford can be sewed to the upper while the elements of the shoe, pump or oxford remain on the last, thereby obtaining a saving in labor, as the 15 shoe remains on the original last until completed thereby avoiding the necessity of second lasting.

A further object of the invention is to provide a shoe last, in a manner as herein- 20 after set forth, for use in connection with the manufacturing of shoes and which eliminates the inner sole at the fore part of the shoe, thereby giving the shoe the flexibility of a hand turn at the front and the stamina, 25 rigidity and high arch support at the rear as is attainable in a McKay process of manufacturing shoes.

A further object of the invention is to provide, a shoe last in a manner as herein- 30 after set forth for use in connection with the manufacturing of shoes and which gives smoother inside sole on which the foot rests, eliminates tacks which are employed in the McKay process or method and further eliminates heavy rough seams inside of the completed shoes which are present in the hand turned production of shoes.

Further objects of the invention are to provide, in a manner as hereinafter set forth 40 a shoe last for use in connection with the manufacturing of shoes, and which is simple in construction and arrangement, strong, durable, compact, thoroughly efficient in its use, conveniently employed, and comparatively inexpensive to manufacture.

With the foregoing and other objects in view, the invention consists of the novel construction, combination and arrangement 45 of parts as hereinafter more specifically described and illustrated in the accompanying

drawings, wherein is shown an embodiment of the invention, but it is to be understood that changes, variations and modifications can be resorted to which fall within the scope of the claims hereunto appended. 55

In the drawings wherein like reference characters denote corresponding parts throughout the several views:

Figure 1 is a section on line 1—1, Figure 3. 60

Figure 2 is a fragmentary view, in longitudinal section, of a shoe last in accordance with this invention taken at the longitudinal median of the last.

Figure 3 is an inverted plan view of the last body with the leather bottom member removed. 65

Figure 4 is a cross sectional view illustrating the position of the elements of a shoe with respect to the last. 70

Referring to the drawings in detail 1 generally denotes a last body which is hollow for a major portion of its length to provide a chamber 2 opening at the top of the body 1. The last body 1 is so constructed as to provide a forward wall 3, a pair of side walls 4, 5, a rear wall 6 and a bottom wall 7 for the chamber 2. The chamber 2 is formed with an open top as indicated at 8. The heel part of the last body 1, which is arranged rearwardly of the wall 6 of the chamber 2 is solid, with this exception that it is formed with a vertically disposed opening 9. That part of the last body arranged rearwardly of the wall 6 is indicated at 10. 85 The last body is set up of the desired contour for the shape of the shoe intended to be made.

The bottom 7 of the chamber 2 is formed throughout the sides and forward end thereof with a slot 11, having one end positioned at one side of the wall 6 and its other end at the other side of the latter. The outer side edge of the slot 11 throughout is arranged in close proximity to the edge of the bottom wall 7. The slot 11 is of appropriate width and of uniform width throughout. The function of the slot 11 will be presently referred to. The open top of the chamber 2 is indicated at 11'. The bottom 12 of the 100

heel part 10 forms a continuation of the bottom wall 7.

The lower face of the body portion 1 is formed of two areas, that is to say the sole part of the last body, and the divisional line between the said areas is indicated at 14. One of the areas is designated at 15 and the other at 16. Securely attached to the area 15 throughout the part thereof between the designations A, B and C is a leather bottom member 17 for the purpose of having the upper leather secured to the bottom of the last and serving the same capacity of holding the upper lasted as the inner sole today serves in holding the upper lasted in the present used McKay process.

The method of making the shoe on a last in accordance with this invention, is as follows:

20 An inner sole or shank piece, not shown, is secured on the sole of the last throughout area 16, but said inner sole or shank piece stops at the divisional line 14 and does not extend upon area 15. After the inner sole 25 of the shank piece is secured in position, the upper leather is lasted over the last, as in a McKay process shoe, but fastened securely to the leather bottom member 17, instead of being fastened to the inner sole of 30 a McKay process shoe as manufactured at present and this does away with the necessity of an inner sole in area 15. An outer sole is then secured to the entire sole shank and heel base of the last in the ordinary 35 manner. After which the McKay stitcher arm is inserted into the chamber 2 and stitches around the inside of the shoe through the slot 11 and under such conditions attaching the upper lasted leather, the shank piece or inner sole and outer sole together only at that part of area 16 provided 40 with the slot and then furthermore stitching and attaching in area 15 the upper lasted leather to outer sole only, thus completing the shoe. In order to free last after 45 stitching is done, the upper must be cut loose from inside of open slot of last. To eliminate roughness the outer sole 18 is cut away, or grooved as at 19 to provide a flush edge.

50 A shoe last in accordance with this invention provides for the saving in labor by sewing the sole while the shoe is on the last, as the shoe remains on the original last until completed, avoiding necessity of second last- 55 ing and furthermore this saves material.

The last further eliminates the inner sole in the fore part of the shoe, thereby giving the shoe the flexibility of a hand turn in area 15 and the stamina, rigidity and high arch support in area 16. Further it provides a smoother inside sole on which the foot rests, eliminates the tacks employed in a McKay process and further eliminates heavy rough seams inside of hand turned shoes, therefore it is thought the many ad-

vantages of a shoe last in accordance with this invention, can be readily understood, and although the preferred embodiment of a shoe last, in accordance with this invention, is as illustrated and described, yet it is 70 to be understood that changes in the details of construction can be had which will fall within the scope of the invention as claimed.

What I claim is:

1. A shoe last comprising a last body 75 formed with a chamber provided with a bottom wall, said chamber extending at a point between the transverse median and rear end of the last body to the front end of the last, the bottom wall of said chamber forming a 80 portion of the sole of the last, said bottom wall having its sides throughout and its forward end slotted, and a flexible bottom member secured to the outer face of the forward portion of said bottom wall and registering 85 with the inner wall of said slot.

2. A shoe last comprising a last body having the major portion of its length hollow to form a chamber extending from a point removed from the rear end of said last body 90 and terminating at its forward end of the latter, said last body having the sole part thereof formed with a slot coextensive with the sides and forward end of the bottom of said chamber and positioned in proximity 95 to the edge of the sole part of the last body, the ends of said slot opposing and spaced from each other at the rear wall of said chamber, and a flexible bottom member secured to the outer face of the sole of the 100 last body at the forward portion thereof and flush with the inner wall of the slot.

3. A shoe last comprising a last body having the major portion of its length hollow to provide a chamber, said chamber extending 105 from a point removed from the rear end of the last body and terminating at the forward end of the latter and having its bottom wall formed with a lengthwise extending slot, said slot having its outer wall 110 positioned in proximity to the edge of the sole part of the last body, said slot coextensive with the sides and forward end of the bottom wall of said chamber and conforming in contour to the shape of the sole 115 part of the last body, said slot having its ends positioned at the rear end of said chamber and spaced from each other, and a leather bottom member secured to the forward portion of the sole part of the last body 120 and flush with the inner wall of said slot.

4. A shoe last comprising a last body provided with a lengthwise extending chamber, said chamber having its rear end positioned at a point between the transverse median and the rear end of the heel body and having its forward end arranged at the forward end of the sole body, said last body having a sole part thereof formed with a slot extending from the rear end of said chamber 125 130

at one side thereof to the rear end of said chamber at the other side thereof, the outer wall of said slot arranged in proximity to the edge of the sole part of the last body at

5 each side thereof and around the toe of the sole part and being of uniform width from end to end, and an upper attaching member

secured to the outer face of the sole part of the last body at the forward portion thereof and flush with the inner wall of the said 10 slot.

In testimony whereof, I affix my signature hereto.

VICTOR V. PESSEMIER.
